RADIATOR HANGER

Filed Feb. 1, 1926

Inventor

Harry H. Crawford
by Arthur W. T. H. H. Crawford

UNITED STATES PATENT OFFICE.

HARRY H. CRAWFORD, OF CHICAGO, ILLINOIS.

RADIATOR HANGER.

Application filed February 1, 1926. Serial No. 85,109.

This invention relates to improvements in radiator hangers and it consists of the matters hereinafter described and more particularly pointed out in the appended claims.

5 The primary object of the invention is to provide a simple and efficient hanger for supporting heating radiators upon building walls, which hanger may be readily produced from sheet metal whereby the cost of manufacture is greatly reduced.

A further object of the invention is to provide a two piece hanger including a wall plate and a radiator hub receiving bracket which is capable of an adjustment with

15 reference to the wall plate, whereby the brackets may be so disposed to support the radiator for the best drainage of the water of condensation therefrom when steam is the heating medium employed.

20 These objects of the invention, as well as others together with the many advantages thereof, will more fully appear as I proceed with my specification.

In the drawings:—

25 Fig. 1 is a view in side elevation of a radiator supported in position upon a building wall by means of a pair of my improved hangers.

Fig. 2 is a vertical section on an enlarged scale as taken on the line 2—2 of Fig. 1.

30 Fig. 3 is another vertical section as taken on the line 3—3 of Fig. 2.

Fig. 4 is a perspective view of a wall plate and associated bracket forming one of my improved hangers, showing the relative positions they occupy when in use.

35 Referring now in detail to that embodiment of the invention illustrated in the accompanying drawings, 1 indicates as a whole one of my improved hangers which comprises but two parts, namely a wall engaging plate 2 and a radiator supporting bracket 3, both preferably made of sheet metal of a suitable gauge. The wall plate is preferably made of strip stock and is much longer than it is wide. Near its top end it is provided with a hole 4 and its bottom end is bent forwardly at a right angle to form a toe or flange 5. In said wall plate, below the hole 4 is provided a relatively narrow, longitudinally extending slot 6.

40 The radiator supporting bracket includes a back flange 7 of a width approximating that of the wall plate and a three sided body 8 extending at a right angle to the flange along one edge thereof. Said body along its

top edge is of width much greater than the flange but said body is cut away from its outer top end corner to its inner lower end corner as best shown in Figs. 2 and 4. In the top edge of the body bracket, near its outer end is provided an upwardly opening recess 9. In the back flange 7 near its top end is provided a longitudinal slot 10 of a diameter at least equal to that of the hole 4 in the wall plate and below said slot 10 is another longitudinal slot 11 which is of a width equal to that of the slot 6 in the wall plate and with which it coacts as will later appear.

45 In Figs. 1 and 2 I have shown two of my improved hangers employed to support a radiator upon a furred brick wall 12 of a building. During the erection of such a wall, hook bolts 13 are embedded between two courses of brick a predetermined distance apart and at the desired height therein, with the threaded end of the bolts projecting far enough inwardly beyond the furring strips 14 and lath and plaster finish 15 thereon. When used in connection with a furring strip, I prefer to provide a spacing sleeve 16 on each bolt in the plane of the furring strip, only one of which is shown in Fig. 2, said sleeve being placed on the bolt before the lath and plaster is applied to the wall. A pair of wall plates is then placed in position with the threaded end of a bolt 13 extending, one through a hole 4 in each wall plate. In public garages and similar buildings where plastered walls are necessary, I apply a plate to each bolt, with the plate directly engaging the inner surface of the brick wall. In concrete buildings such hook bolts may or may not be employed and when not employed, I prefer to use expansion shells (not shown) embedded in the wall to receive such bolts.

50 A bracket 3 is then applied to each wall plate with the threaded end of the bolt extending through the slot 10 therein after which a nut 17 is applied to the bolt end and drawn up tight. With the parts in this position, portions of the slots 11 in the bracket flanges 7 will overlap portions of the slots 6 in the wall plates whereafter a spike 18 is driven through each set of said slots to enter the mortar between courses of brick, as best shown in Fig. 2. It is desirable to position one bracket on its wall plate, a short distance higher than the bracket on the other wall plate so that when a steam

radiator 19 is hung thereon, it will be tilted toward its inlet end for better drainage of the water of condensation therefrom. In hanging the radiator the same is lifted upwardly so that the brackets 3 will extend between two of the sections 20—20 of the radiator where the hubs 21 of said sections will seat in the recesses 9 of said brackets and the toes 5 of said wall plates will engage with opposed sides of said sections so that the radiator cannot shift and, at the same time acts to hold the wall plate against the wall as is apparent. Should it be necessary ever to remove the radiator, the steam pipes are removed and the radiator lifted off the brackets.

My improved hanger possesses many advantages. It may be made at a relatively low cost and although it is light in weight it is strong and rigid and will easily bear the strain imposed upon it in use. The hangers may be readily installed and when supporting a radiator are not so noticeable as to be objectionable on that account. In the use of the spacers 16 in a furred wall, the danger of cracking the plaster finish is eliminated by the impossibility of drawing up the nuts 17 too tight.

While in describing my invention, I have referred to certain details of mechanical construction as well as form and arrangement of the parts thereof, the same is to be taken as by way of illustration only and not by way of limitation except as may be pointed out in the appended claims.

I claim as my invention:

1. A radiator hanger embodying therein, a wall plate and a hanger bracket extending at a right angle therefrom and including a flange for adjustable engagement with said wall plate, a bolt adapted to extend

through said flange and wall plate and to be fixed in a building wall, and a member on the bottom end of said wall plate and adapted to engage between adjacent sections of the radiator supported by the hanger to prevent shifting thereof.

2. A radiator hanger embodying therein, a wall plate having a hole near its top end and an outwardly extending toe at its bottom end, a hanger bracket extending at a right angle therefrom and having a flange adapted to be engaged against the top end of said wall plate, there being a slot in the top end of said bracket flange to receive a bolt which passes through said wall plate hole into a building wall, said flange and wall plates having cooperating slots below the bolt and through which a member may be positioned in said wall, said hanger bracket having a recess in its top edge to receive the hub portions between adjacent sections of the radiator supported by the hanger.

3. In combination with a furred and plastered building wall having a bolt positioned therein, a radiator hanger comprising, a wall plate adapted to engage against the plaster and a bracket plate including a flange to engage the wall plate, said wall plate and flange having openings therein to receive the bolt positioned in said building wall, a spacing sleeve on the bolt between the wall plate and wall, means for operatively connecting said wall plate and flange together at a point below the bolt, and a toe on said wall plate to engage opposed surfaces of adjacent radiator sections.

In testimony whereof, I have hereunto set my hand, this 28th day of January, 1926.

HARRY H. CRAWFORD.
